UNITED STATES PATENT OFFICE.

ALEXANDER SMITH, JR., OF NEW YORK, N. Y.

FOOT-PRESSURE REFLECTOR.

1,334,810.

Specification of Letters Patent. Patented Mar. 23, 1920.

Application filed December 6, 1919. Serial No. 343,074.

To all whom it may concern:

Be it known that I, ALEXANDER SMITH, Jr., a citizen of the United States, and resident of the city of New York, borough of Manhattan, and county and State of New York, have invented a new and Improved Foot-Pressure Reflector, of which the following is a full, clear, and exact description.

This invention relates generally to surgical appliances, and more particularly to a device adapted for use by podiatrists, chiropodists and orthopedic doctors in examining foot ailments such as Morton toe, weak and flat feet, etc., and to enable them to make a proper diagnosis.

Heretofore in diagnosing foot ailments, the doctor has been unable to determine exactly what portions of the sole of the foot presses upon a supporting surface so that it has made it difficult for the doctor to prescribe the proper means for correcting a certain ailment.

One of the objects of this invention is to provide an appliance, and an improved method of examining the sole of a foot whereby the difficulties above noted are overcome, and a device provided which will permit a reflected image of the sole of the foot under pressure to be observed. In carrying out the method, use is made of the principle that pressure applied to a part of the body produces a temporary anemia of that part which presents a white area at the parts under pressure, the other parts not directly under pressure, presenting a reddish appearance.

A further object of this invention is to provide an improved method of diagnosing foot ailments which will enable the proper prescription to be made for building up a proper brace or support.

In the broad aspect, the above objects are accomplished by providing a transparent support such as glass, on which the foot may be pressed, and by arranging a reflecting surface therebelow so that the entire sole of the foot may be seen, and the parts under pressure, and those spaced from the glass may be observed by noting the white and reddish appearances of the sole as a reflected image.

Other objects and advantages will be apparent from the following description and the accompanying drawing forming a part of the specification, and showing for example one practical embodiment of the invention,

In the accompanying drawings, similar characters of reference designate corresponding parts in the several views.

Figure 1 is a sectional view showing a device embodying the invention, representing a foot pressed upon the transparent medium, and showing the manner in which the condition of the foot may be observed, by different persons.

Fig. 2 is a transverse sectional view looking in the direction of the arrows and taken generally on the line 2—2 of Fig. 1 indicating the manner in which the reflected image appears.

Fig. 3 is a view looking in the direction of the arrows and taken on the line 3—3 representing the reflected image of the sole of the foot and indicating certain portions of the sole under pressure.

With reference more particularly to the accompanying drawings showing for example one practical embodiment, a transparent medium 1 which is made of plate glass or other suitable material, is carried in a support 2 or box like structure open at the top, and may be of any suitable construction. As shown, the transparent medium 1 is held in a recess 3 formed at the top edge of the side supports, and a suitable molding 4 holds the transparent medium in proper position, but it is to be understood that this invention is not to be limited to certain details of construction shown herein, but may be changed and varied to suit different conditions and individual preference. The transparent medium 1 is of sufficient thickness to function as a support or rest for a foot 5, the sole 6 of which may be pressed upon one side 7 thereof.

A suitable reflector 8 is shown angularly arranged and spaced from the other side 9 of the transparent member 1, so that a person as for instance a doctor looking for a point 10 in the reflector 8, may see or observe a reflected image of the sole 6 of the foot, which would appear for instance as illustrated in Fig. 3. If desired, another reflector 11 may be angularly arranged below the transparent medium 1, so that another person as for instance the patient looking from the point 12 may also observe a reflected image of the sole of the foot from the reflector 11. In the form shown, bracing members 13 and 14 are provided for the reflectors 8 and 11 respectively, but it is understood that any suitable ar-

rangement of the reflector may be provided. If desired, a source of illumination preferably an electric bulb 15 may be provided, together with a reflector or shade 16 therefor.

In operation, the patient presses the sole of the foot upon the transparent medium 1, which will cause certain portions of the sole as for instance the heel 17, the ball 18, and 10 a certain portion of the toes 19 to be flattened, as indicated in Figs. 2 and 3, which flattened portion will be caused by a pressure upon the sole, causing anemia, and will show up as a white area. Those other portions of the foot which are not pressed against the member 1 will usually appear reddish in color. Such a condition becomes visible to the practitioner, and enables him to better diagnose the foot ailments, and will 15 better enable him to determine what portions of the foot are to be braced and supported. Thus, it will permit him to build up little by little underneath the sole, and can then observe the proper mount to be 20 added. In this way, the doctor can be sure in making a prescription for a support, that the support is properly placed, and is raised to the proper degree, whereas, heretofore 25 this has not been possible.

It is to be understood that while a certain practical embodiment of the invention has been shown herein that various changes and modifications may be made therefrom without departing from the spirit and scope of 30 this invention.

Having thus described my invention, I claim as new and desire to secure by Letters Patent:

1. A device of the character described 40 comprising a transparent medium adapted to have the sole of a foot pressed on one side thereof, and a reflecting surface spaced from

the other side of said transparent medium and arranged to permit the reflected image of the sole to be observed.

45

2. A foot pressure reflector comprising a support, a transparent medium arranged therein, and a medium having a reflecting surface being spaced from and arranged below the said transparent medium, so that a 50 reflected image of the sole of a foot pressed upon one side of the transparent medium may be observed.

3. A foot pressure reflector comprising a support, a plate of glass supported thereby and adapted to function as a support for a foot, a reflector angularly arranged below the plate of glass and spaced therefrom, whereby a reflected image of the sole of the foot may be visible from above.

55

4. A device of the character described comprising in combination a support, a transparent medium held by said support and adapted to function as a rest for the sole of a foot pressed on one side thereof, 65 and a plurality of reflectors spaced from and angularly arranged below said transparent medium, whereby a reflected image of the sole of the foot may be observed from different positions.

70

5. A device of the character described comprising in combination a support, a transparent medium held by said support and adapted to function as a rest for the sole of a foot pressed on one side thereof, 75 and a plurality of reflectors spaced from and angularly arranged below said transparent medium, whereby a reflected image of the sole of the foot may be observed from different positions, and a source of light arranged between the transparent medium and the reflectors.
